UNITED STATES PATENT OFFICE.

GEORGE WILKINSON, OF PROVIDENCE, RHODE ISLAND, ASSIGNOR TO THE GORHAM MANUFACTURING COMPANY, OF SAME PLACE.

DESIGN FOR A SPOON.

SPECIFICATION forming part of Design No. 21,605, dated June 7, 1892.

Application filed May 3, 1892. Serial No. 431,726. Term of patent 7 years.

To all whom it may concern:

Be it known that I, GEORGE WILKINSON, a citizen of the United States, residing in the city of Providence, county of Providence, and State of Rhode Island, have invented and produced a new and original Design for Spoons, of which the following is a specification, reference being had to the accompanying drawing, forming part thereof.

10 The drawing represents an obverse view of the spoon, illustrating my new design. The leading features of my design for spoons consist in the wave-like outlines forming alternating enlargements and slight contractions in the width of the handle and increasing the width of the same toward the upper end; double border-lines extending upward from the bowl and connected by two inward curves; a 15 meeting-point of these curves; a central longitudinal convex portion extending along the neck of the handle, widening with the outline of the handle and being flattened toward the upper end; double border-lines extending on either side of the convex portion and practically parallel with the outline, the outer border-line being turned inward at intervals and forming foliations extending partially over the convex portion; longitudinal bead- 20 ings extending along the apex of the convex portion and branching outward at the upper ends; scrolled beadings extending upward and inclined outward to form the lower end of a panel-frame; foliated scrolled lines forming 25 the sides of the panel, and a shell-like finial at the upper end of the handle, and a representation on the panel of three persons kneeling in apparent devotion before one who is standing with one arm thrown around the figure of a boy, a vessel being shown at the right and buildings indicated in the left background.

30 Number 2 in the drawing designates the bowl of a spoon, of which 3 is the handle. The inner surface of the spoon may be ornamented 35 with a representation of an exposition building. From the bowl 2 the outline of the han-

dle extends upward and curves slightly outward to 4 4, then is slightly contracted to 5 5, and curves outward and upward, again slightly outward to 6 6, whence it is very slightly contracted in a gentle curve, then increasing to a bolder curve in the outward direction, and finally curving inward to meet the projections 7 7, which are joined by a curved line 8, forming the upper end of the handle. The 40 lower end of the handle is ornamented by the double border-lines 9 9, the upper ends being joined by double inward curves. Above the junction of these lines is a small scroll 10, having depending ends. The central portion 45 of the neck of the handle is raised to form the rib 11, the convexity of which becomes less marked toward the upper end, and the central portion or apex of this rib is ornamented by the beadings 12 12, which branch outward 50 at the upper ends. Extending practically parallel with the outlines of the gradually-widening neck are the double border-lines 13 13, the outer of which is turned inward onto the rib 11 at 14 14 to indicate foliations lapping 55 over the same. At the enlargement 4 4 these lines are ended in scrolls curved inward. Extending upwardly and curving outward from the ends of the beadings 12 are the scrolls 15 15, forming the lower end of the panel-frame, 60 the side borders of which are formed by the foliated scrolled lines 16 16, the upper ends ending in the projections 7 7 and being separated by the shell-like finial 17, having a 65 scrolled base.

On the panel of the handle are depicted three persons kneeling in apparent devotional reception of one who has evidently landed from a vessel (seen at the right) and stands with one arm thrown about a younger person.

What I claim is—

The design for a spoon, as herein shown and described.

GEORGE WILKINSON.
